UNITED STATES PATENT OFFICE.

CLAIR G. WRIGHT, OF KANSAS CITY, MISSOURI.

UNION-GARMENT.

1,281,473.

Specification of Letters Patent. Patented Oct. 15, 1918.

Application filed October 15, 1917. Serial No. 196,627.

To all whom it may concern:

Be it known that I, CLAIR G. WRIGHT, a citizen of the United States, residing at Kansas City, in the county of Jackson and 5 State of Missouri, have invented certain new and useful Improvements in Union-Garmets; and I do declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 My invention relates to improvements in union garments, and has for its principal object to provide a two-piece garment wherein the parts are so constructed that the suit may be worn with the convenience and comfort of the usual one-piece union garment, and which may be readily separated to permit the replacing of one portion without a necessary replacing of the other portion.

It is a further object of the invention to 25 provide a convenient and serviceable connection for the parts of the garment whereby the lower may be supported from the upper garment and the latter prevented from working from beneath the lower garment.

30 In accomplishing these objects, I have provided improved details of structure, the preferred forms of which are illustrated in the accompanying drawings, wherein:—

Figure I is a front and side view of a person clothed in a garment embodying the 35 present invention.

Fig. II is a back view of the same.

Fig. III is a detail view particularly illustrating the application of the connecting 40 tabs to the fastening devices of the upper garment and to the belt portion of the lower garment.

Fig. IV is a sectional view of a portion of the connected garments and the connecting tab.

Referring more in detail to the drawings:

1 designates the upper, or shirt portion, and 2 the lower or trousers portion of a garment constructed according to the present 50 invention; the parts being patterned after garments of this character in general use except in features hereinafter mentioned, and may be made of any suitable material, but in the present instance heavy cloth ordinarily known as "overall" goods is preferable.

In working garments of this character, it is usual that the lower portion wears out much before the upper portion, and should the garment be made all in one piece, replacing of the worn portion necessitates the purchase of an entire garment, and the discarding of a garment wherefrom its full value has not been received. It is, therefore, the object of the present invention to provide a 60 garment wherein the upper and lower portions are so connected that the garment may be worn with the same convenience and comfort as the ordinary union garment, but wherein the parts may be readily disconnected so that one of the portions may be used interchangeably with other like garments so that the full value may be derived 65 from each garment before it is discarded.

To effect the union of the upper and lower 70 garments, I provide the trousers, about the waist band, with a plurality of spaced "tunnel" loops 3 through which an ordinary leather or cloth belt 4 is extended, and attached at spaced intervals about the waist 75 portion of the shirt, are the head portions 5 of fastening devices, the coöoperating cap portions of which are fixed in loop tabs 7 which are located in registration with the spaces between the loops 3 so as to slidably 80 receive the belt to coöperate with the said loops to form a union of the upper and lower 85 portions of the garment.

The connecting means for attaching the 90 loops 7 to the shirt portion of the garment may be of any suitable type, but preferably comprises the ordinary "glove fastener" as shown, which provides a serviceable connection, but which may be pulled apart when it is desired, so that the tabs may be 95 disconnected from the upper garment to disconnect the members.

The number of connecting loops employed is immaterial, so long as enough are used to properly connect the portions of the garment, and while I have shown the trousers equipped with the tunnel loops, it is not essential that this particular type be used, as the ordinary belt loop may be used with like results.

Assuming that a garment comprising upper and lower portions of this character is provided, and that the said upper and lower portions are connected by the belt and tab arrangement, as described, it is apparent that 110 should the wearer desire to replace either of the portions of the garment, he may discon-

nect the same by disconnecting the tabs from the upper garment so that the portions of the garment may be separated. The new part of the garment may then be attached to 5 the portion of the garment not discarded to produce a complete garment.

It is apparent that a number of shirt parts of various weights could be provided, which would fit a lower garment, so that a wearer 10 could change as he desired according to weather or other conditions, or that two or more lower garments could be made for each upper garment so that should the lower garment receive more wear than the upper, full 15 value of the latter may be had before it is necessary to be discarded.

Having thus described my invention, what I claim as new therein, and desire to secure by Letters-Patent, is:—

20 1. A garment of the character described, comprising upper and lower body portions, belt loops formed at spaced intervals about the waist line of the lower portion, a belt ex-

tended through said loops, independently formed supporting loops applied to the belt 25 between the said belt loops, and means for removably connecting the supporting loops to the upper garment.

2. A garment of the character described, comprising a lower body portion and an 30 upper body portion adapted to extend beneath the lower body portion, belt loops formed in spaced relation about the waist line of the lower garment, a belt extended through the said loops, independently formed 35 supporting loops applied to the belt between the lower garment loops, fasteners permanently fixed to the upper garment at intervals corresponding to the spacing of the belt loops and coöperating members fixed to the 40 supporting loops adapted for yieldable attachment to or detachment from said fasteners on the upper garment for the purpose set forth.

In testimony whereof I affix my signature. 45
CLAIR G. WRIGHT.
